UNITED STATES PATENT OFFICE.

JOHN ALLEN HEANY, OF NEW YORK, N. Y., ASSIGNOR, BY MESNE ASSIGNMENTS, TO
ROCKBESTOS PRODUCTS CORPORATION, A CORPORATION OF DELAWARE.

WIRE-COVERING MACHINE.

1,375,655.

Specification of Letters Patent. Patented Apr. 19, 1921.

Application filed February 10, 1916. Serial No. 77,452.

To all whom it may concern:

Be it known that I, JOHN ALLEN HEANY, a citizen of the United States, residing in the city, county, and State of New York, have invented certain new and useful Improvements in Wire-Covering Machines; and I do hereby declare the following to be a full, clear, and exact description of the invention, such as will enable others skilled in the art to which it appertains to make and use the same.

The invention relates to machines for covering wire with insulation and the like, and has for its object to provide a simple, efficient and rapid machine adapted to apply tenuous and fragile threads or filaments, coated with asbestos or similar fibers, to the surface of electric wires and other conductors; associated with means for impregnating the covering with a suitable material, such as water-proofing and fire-proofing compounds; means for finishing, smoothing and compacting the impregnated covering on the wire; means for drying the coated wire before the same leaves the machine, and a coördinated system of instrumentalities for operating the various elements of the machine to maintain the necessary tension on the wire and the covering material, and to prevent excessive strains, which would tend to rupture either the wire or the fiber-coated filamentary body which constitutes the covering.

The invention is illustrated in the accompanying drawings, in which,

Figure 1 is a front elevation of a multiple spindle machine, certain of the parts being broken away and other parts being shown in section.

Fig. 2 is a side elevation of the machine with certain of the parts in section.

Fig. 3 is an enlarged detail of the finishing device.

Fig. 4 is a sectional detail of the finishing device.

Fig. 5 is a sectional plan view of the same.

Fig. 6 is an enlarged plan view of the drawing mechanism.

According to the drawings, 1 indicates the main frame or support of the machine, which may be of any desired size to carry any desired number of sets of covering and finishing mechanism. Said machine involves a horizontal table or rail 2 running

across the same and adapted to constitute the lower supporting element, from which rises two end standards 1' carrying a top rail 3, which likewise extends throughout the length of the machine.

As indicated, the mechanism for covering the wire and finishing the covering may be multiplied and a description of one set of such apparatus will apply to the others.

Mounted in a suitable vertical sleeve-like bearing 11 secured to the upper rail 3 is a rotary flier spindle 10 having a longitudinal bore through which the wire to be covered passes. Mounted on the lower portion of said spindle and journaled thereon by means of ball bearings 13 and 14, is a sleeve 12, which is adapted to receive and support a cop or ball A of thread or the like, which is to be wound about the wire to constitute a covering for the same. This covering cord or thread may consist of a relatively fine thread of cotton, yarn, or the like, which is provided with a superficial coating of fibers of asbestos or other suitable material, of any desired thickness, which fibrous coating constitutes the practical insulating sheath for the wires to be covered, the cord or thread serving as a base or foundation for the fibers. In order to regulate the tension of the fiber-covered thread as the same is drawn off the top A, there is provided a helical spring 15, surrounding the spindle 10 and bearing at one end on the raceways of the lower ball bearing 14, the tension of said spring being adjusted by means of a set nut 16 screw-threaded at the spindle. By adjusting said nut 16 the spring 15 is regulated to vary the thrust between the ball bearings and thereby regulate the amount of tension on the thread necessary to rotate the cop-holding sleeve 12.

Keyed to the spindle 10 above the cop-holding sleeve 12 is a disk or fly wheel 19 which serves to steady the rotary movement of the flier and to produce a gradual acceleration of the flier when the machine is started, and effect a correspondingly gradual retardation of the flier when the machine is to be stopped, in order that no sudden strains may be imposed upon the thread as the same is drawn off from the cop A and laid up on the wire.

Mounted in the disk 19, laterally of the spindle 10 is a stud 20 carrying a sleeve 20'

upon which sleeve is supported a generally helical or convoluted thread guide 21, which serves to guide and direct the thread from the cop A on to the wire, as will be understood. The sleeve 20' is normally locked to the stud 20 by means of pin and slot connection at one end and a nut threaded to the other end of the stud. By backing off the nut sufficiently to permit the pin and slot engagement between the sleeve and stud to be separated, the sleeve and the thread guide may be rotated sufficiently to swing the outer end of the thread guide away from the wire, for purposes of adjustment and repair when necessary.

Preferably, the lower end of the spindle 10 is provided with a perforated thimble 17 which serves to accurately guide and center the wire passing through the spindle 20 and said thimble is removably secured to the spindle by means of a flanged nut 18. The said thimble 17 is therefore interchangeable and multiple thimbles of this character may be provided with openings 25 of different sizes to accommodate the different sizes of wire to be covered by the machine.

Mounted on the lower rail 2 and in axial alignment with the spindle 10 is a tube 22 having a flanged base 23, which tube is adapted to support a series of cops or balls A of the covering material, as a reserve supply, and which may be moved successively into engagement with the spindle 10, as the preceding cop carried thereby is exhausted, so that relatively great lengths of wire may be covered without breaking the wire to enable a fresh cop of covering material to be placed in position on the flier spindle.

40 Mounted on the upper rail 3, in suitable journal bearings, is a stub shaft 25 having loosely mounted on one end thereof a guide pulley 26 adapted to receive the bare wire from the source of supply and direct the same into the hollow spindle 10. In order that the shaft 25 may impart rotary motion to the guide pulley 26 and also permit the latter to slip in case tension on the wire becomes excessive, said pulley is adapted to 45 be connected to the shaft by means of friction collars 27, 27, fixed to the shaft, the outer one of said collars 27 being slidably mounted on the shaft and held in frictional engagement with the hub of the pulley 26 by means of the helical spring 28, the tension of which may be adjusted by means of a set nut 29 so that the said pulley 26 may be clamped between said collars with a predetermined amount of pressure.

50 Mounted upon the other end of the stub shaft 25 is a second grooved pulley 30 which serves as a pull-off for the wire, after the latter has been covered and finished by the machine in the manner to be hereinafter described. Said pulley 30 is provided on its

inner edge with gear teeth 31, which mesh with a pinion 33 carried by a swinging arm 34 adjustably connected to the upper end of bracket 31' and provided with a handle 35 by means of which the pinion 33 may be 70 swung into and out of engagement with the driving gear 32 mounted upon a second stub shaft carried in bracket 31' on the opposite end of which stub shaft is mounted a worm gear 37. The gear 32 and pinion 33 are removable and interchangeable with other gears and pinions of different sizes to vary the speed of the pulley 30 and shaft 25.

Journalized in the rails 2 and 3 is a vertical shaft 45 to the upper end of which is secured a gear wheel 40 which meshes with a pinion 41, journaled on the upper rail 3, which meshes in turn with a pinion 42 mounted on a vertical worm shaft 38 and with a pinion 43 secured to the upper end 80 of the spindle 10 so that the rotation of shaft 45 imparts rotary movement to a pulley 30, shaft 25 and to the flier spindle 10. The worm on shaft 38 engages the worm wheel 37 which in turn drives gear 32 and pinion 33, as hereinbefore explained.

Secured to the lower end of the shaft 45 is a friction disk 48, which is adapted to alternately engage with a friction plate 47 secured to the under face of the bottom rail 2, and with a second friction disk 49, journaled in a vertical bearing 46, secured to the upper side of rail 2, and provided with a hollow stem to the upper end of which is connected a pinion 50, which meshes with a gear 51, mounted on a short vertical stub shaft on the rear portion of rail 2 and carrying on its upper end a beveled pinion 51', which meshes with a beveled gear 4' secured to the main drive shaft 4, which runs longitudinally of the machine and is provided with a suitable drive pulley 5 associated with the usual loose pulley 5', adapted to engage a belt from any appropriate source of power.

Secured to the upper face of rail 2 are two vertical rods or standards 60 connected at their upper extremities by a transverse yoke 60', and having attached intermediate their ends, a horizontal bracket 61 which carries a threaded sleeve 62. Slidably mounted in the yoke 60' is a sleeve 65 which cooperates with a collar 66 pinned to shaft 45 and between which collar and the upper end of the sleeve 65 there is located an anti-friction bearing 67. Surrounding the shaft 45 and confined between the collar 65 and an adjusting nut 63 on the sleeve 62 is a helical spring 64 which normally tends to lift the sleeve 65 and with it the shaft 45. Surrounding the shaft 45 below the bracket 61 is a second helical spring 68 which is confined between a collar 70, fast to the shaft 45, and an adjusting nut 69 carried by the threaded sleeve 62, which helical spring nor- 130

normally tends to move shaft 45 downwardly. The springs 64 and 68 are so adjusted that the former predominates and when under a strain moves the shaft 45 upwardly a slight 5 distance until the friction disk 48 engages co-operating friction disk 49 and rotary movement is imparted to said shaft 45 and to the various parts of the mechanism geared thereto. In order, however, to overcome the 10 thrust of spring 64 and therefore move the shaft downward until the friction disk 48 thereon engages the braking surface 47, there is provided a bell crank lever 71 which co-operates with sleeve 65 and with a 15 suitable starting handle connected with the drying mechanism, to be hereinafter described, so that when said bell crank is moved in one direction, it exercises a counter pressure against spring 64, thereby permitting 20 the lower spring 68 to force the shaft 45 downward and engage friction disk 48 with the braking surface 47. When the pressure on said bell crank 71 is relieved, the upper spring 64 again comes into play and moves 25 collar 65 and shaft 45 upward, thereby disengaging friction disk 48 from the braking surface 47 and bringing said friction disk into operative engagement with the driving friction disk 49.

30 The friction disks 48 and 49 and the braking surface 47 are so constructed and arranged that the friction disk 48, which is intermediate the disk 49 and the braking surface 47, will slip under excessive strain, 35 and will also be gradually accelerated in starting the machine and gradually retarded in stopping, so that in both the starting and stopping operations, no excessive shocks or strains will be imposed upon any part of 40 the mechanism.

On the extreme lower end of the shaft 45 is secured a gear 71, which meshes with an idle pinion 72 journaled on a short stub shaft projecting vertically from the under 45 side of the bottom rail 2. Said pinion 72 serves to drive a pinion 73, attached to the lower end of a rotary hollow spindle 74, which is journaled in suitable bearing plates attached to the upper and lower faces 50 of the rail 2, as more particularly shown in Fig. 1. Said spindle 74 constitutes the rotary driving element of a device designed to smooth, compact and finish the covering which has been laid up on the wire by the 55 flier, after the coating has been impregnated with a suitable water-proofing or fire-proofing compound.

The latter is applied to the covered wire by passing the wire over a guide pulley 92 60 journaled in a pendent bracket 93 projecting from the under side of the rail 2. The lower peripheral edge of the pulley 92 dips into a shallow pan 91, which is removably supported in bracket arms 91' and 91'', 65 which pan is adapted to hold the impreg-

nating compound, which is preferably in a liquid or semi-liquid condition and is susceptible of rapid drying. After the wire has been covered with the material from the cop A by the operation of the flier mechanism, it passes through the cop magazine tube 22, under guide pulley 92, thence upwardly through the hollow spindle 74 of the finishing device.

The finishing device, more particularly 75 illustrated in Figs. 3, 4 and 5, comprises the rotary spindle 74 journaled in the bearings 74', 74'', and having secured to its upper end a frame consisting of a lower disk 75, an upper disk 75' connected together by 80 suitable sleeved spacing bolts 76. Secured in a triangular opening in the upper end of the shaft 74 is a generally triangular die 77 having a channeled face 78, the channel or groove of which lies in the longitudinal 85 axis of said shaft 74. The upper end of the die 77 is provided with a beveled surface which is engaged by a set screw 79 which is threaded in a socket in the upper plate 75' and by means of which the die 77 may be 90 adjusted toward and from the axial line of the spindle 74. The wire passing from the guide pulley 92, vertically and axially through the spindle 74, engages the groove or channel 78 in the die 77, and is smoothed, 95 compacted and finished by the revolution of said die and coacting pressure plates 82, which engage the surface of the wire at intervals, opposite the groove 78. The pressure plates, four of which are illustrated, 100 are mounted upon the vertical shaft 80, which is journaled in cone bearings in a lower bearing member 80' to which the shaft is connected by a pin and slot, and in an upper adjustable bearing stud 80'' which 105 is threaded into the upper disk 75'. Each of said pressure plates is carried by a bifurcated yoke 81, the arms of which engage shaft 80 and are held in proper position by means of collars 84 which are locked to the 110 shaft 80 by means of bolts 85. Each yoke piece 81 is engaged on its outer face by means of a spring 83, secured to the co-operating collar 84, which spring tends to force the yoke and the pressure plate carried thereby into engagement with the wire passing through the die. The shaft 80 and the yoke carried thereby are normally held in operative position by means of a latch 115 86 engaging a notch in the lower bearing 120 80' and held in locking position by means of the spring 87. In order to regulate the spring pressure of the individual pressure plates, the collars 84 are adjusted circumferentially about the shaft 80 by means of 125 the bolts 85, as will be understood. In order to move the pressure plates from engagement with the wire, the latch 87 is released and the shaft 80 turned by means of the handle 80'', which operates in a 130

horizontal slot in the lower disk 75. As the covered wire is drawn through the finishing device, the latter is rotated about its vertical axis, the rotary motion being imparted 5 to the hollow spindle 74 by means of pinion 73 as hereinbefore described, which rotary motion is imparted to the frame consisting of the upper and lower disks 75, 75' with their connecting bolts, which in turn rotate 10 the channeled die 77 and the pressure plates 82 in contact with the wire, so that the covering thereon is smoothed, compacted and finished and any excess amount of the impregnating compound which may adhere to 15 the wire is removed and flows back into the surrounding receptacle 88, whence it flows through a bottom opening 89 and a discharge pipe 90, back into the pan 91. It will be noted that the channeled die 77 and 20 the coöperating pressure plates are revolved about and in close contact with the wire and serve to produce an even, uniform and substantially homogeneous texture to the impregnated covering, so that the latter requires only to be dried effectively, before 25 being delivered from the machine in finished condition. By adjusting the longitudinal channel die 77 and also the degree of spring pressure on the pressure plates 82, it will be apparent that any desired degree of 30 compactness and homogeneity can be imparted to the covering. When it is found necessary to clean the apparatus, or adjust or renew the die 77 and pressure plates, the latter may be swung away from the die by 35 means of the handle 80", whereupon the die 77 may be removed and ready access to the pressure plates and their supporting devices effected.

40 After the covered wire leaves the smoothing and finishing device, it is passed through a drying apparatus, which is conveniently constructed in the form of a generally cylindrical shell 106 having one side thereof 45 cut away to form a longitudinal slot, which shell is carried by bracket arms 101 and 104. The lower bracket arm 101 is journaled on the coned end of a gas supply pipe 100, which is secured to the bracket 61. The 50 upper bracket arm 104 is secured to a vertical shaft 102, the upper end of which is journaled on the coned end of a set screw 103, on the under side of the top rail 3, the lower end of said shaft being pinned in 55 a socket in the lower bracket 101. The bracket arm 101 is hollow to afford a conduit for gas, which passes to vertical burner pipes 105, carried by the respective bracket arms 101 and 104 and disposed around the 60 cylinder or shell 106, so that the burning gas issuing from the perforations in said pipes impinges against the outer wall of the shell 106 and heats the same to a degree sufficient to thoroughly dry the covering on 65 the wire as the latter is drawn through the

shell. The bracket arm 104 is provided with a cam 108 which coöperates with the vertical arm of the bell crank 71 and operates the said bell crank to effect the starting and stopping operation of the machine. The forward end of the bracket arm 101 is provided with a handle 107, by means of which the entire drying mechanism may be swung to and from operative position. In Fig. 1, the drying apparatus is shown in inoperative position, that is to say, it has been swung away from the wire so that the latter, which is stationary, will not be damaged by the heat developed by the drying apparatus. When the drying apparatus is 75 swung by means of handle 107 to operative position so that the wire is disposed axially within the shell 106, cam 108 passes out of engagement with the bell crank 71, thereby releasing spring 64, which moves shaft 45 upward to the slight extent necessary to engage friction disks 49 and 48 and start the machine in operation. In order to stop the machine, it is necessary to swing the drying device by means of handle 107 to inoperative position, as shown in Fig. 1, which causes cam 108 to engage bell crank 71 and move the same to depress sleeve 65 and spring 64, which has the effect of gradually 80 stopping the machine, as hereinbefore described.

85 The means for supplying the wire to be covered to the machine may consist of any of the usual forms of spools or reels upon which the wire is stored, and which is conventionally indicated at X in Fig. 2, as mounted upon a removable shaft 126 mounted in suitable bearings at the rear part of the machine. As will be apparent, the wire is taken from the spool or reel over the 90 guide sheave or pulley 26, thence through the flier mechanism in a downward direction through the cop storing magazine, under the guide sheave or pulley 92, through the pan of impregnating material, thence 95 upward through the finishing and drying devices to the pull-off sheave or pulley 30, whence it passes to a suitable winding device or reel, which is preferably mounted on the same shaft 126 as the supply spool or 100 reel, and operatively connected to the driving mechanism of the machine so as to be 105 positively rotated to feed or draw the wire through the machine at the proper rate of speed to permit the covering, finishing and 110 drying operations to be effected. The winding spool to receive the finished wire is conventionally illustrated at 125, see Fig. 2, and is adapted to be operatively connected 115 with the driving gear 124, which meshes 120 with the pinion 123 mounted on a counter-shaft 123', which carries a sprocket 123" driven by chain 122 from a sprocket wheel 121, which is revolubly mounted on shaft 125, journaled in brackets on the main 130

frame 1 below the bottom rail 2. To avoid confusion, the driving mechanism for the take-up spool is illustrated in the lower right-hand portion of Fig. 1 and consists of 5 a beveled gear 110 mounted on the hub of idle gear 72, which latter transmits movement from the shaft 45 to spindle 74. The gear 110 meshes with a beveled gear 111 loosely mounted on shaft 120, which gear 10 111 abuts the thrust collar 116 pinned to the shaft 120, with an anti-friction bearing interposed between the gear and the collar. The opposite face of gear 111 is provided with a friction surface which cooperates with a friction clutch 112 which carries driving sprocket 121. A helical spring 113 is interposed between the friction clutch 112 and a set nut 114, which is threaded to a collar 115, which is pinned 15 to the shaft so that by turning the set nut 114, the tension of the spring, and therefore the pressure exerted between the friction surfaces of gear 111 and clutch member 112 may be accurately adjusted. The connecting 20 gearing between the driving shaft 45 and the winding reel 125 is such that gear 111 always runs faster than would be necessary to cause the reel 125 to take up the wire as fast as the latter is fed through the 25 machine by the pull-off sheave or pulley 30. This produces a slipping between the friction disks of gear 111 and clutch member 112, which imparts a certain predetermined tension on the wire, regulated by the 30 spring 113 and also prevents this tension becoming great enough to rupture the wire as it is being wound on the storage reel. Any suitable form of guide mechanism for laying up the wire on the storage reel 35 40 125 may be employed and such form of guide is conventionally illustrated at 130 in Fig. 2.

In Fig. 1 of the drawings, two sets of wire covering mechanism are illustrated, but it 45 will be understood that any number of sets may be employed in a single machine, and that any or all of the sets may be operated as desired. If found convenient or desirable, the supply and storage reels or spools 50 for the respective units may be mounted upon separate stub shafts at the rear of the machine so that it will not be necessary to stop all of the units when it is desired to supply or remove the reels belonging to any 55 particular unit.

The operation of the apparatus will be understood from the foregoing description, and it has been found in practice that machines involving the coördination of parts 60 as set forth operate with great rapidity and accuracy to lay up on the wires or conductors of various sizes, an even, regular and substantially homogeneous covering of any desired thickness, which when suitably 65 impregnated, finished and dried, presents a

sheath of high insulating value, that is effectively resistant to moisture and heat, and which increases the diameter of the covered wire to a lesser extent than any of the former types of insulation possessing the 70 same high insulating factor.

What I claim is:

1. Apparatus for applying insulation or other covering to wires and the like, comprising means for effecting longitudinal movement of the wire in one direction, means for reversing the direction of movement of the wire, means for applying a covering to the wire in advance of the reversing means, means for applying an impregnating material to the covered wire during its passage over the reversing means, ironing and smoothing means arranged above the last-mentioned means to act upon the covered and impregnated wire after it leaves the reversing means, and drying means arranged above the ironing and smoothing means to act upon the wire after it leaves the latter means.

2. Apparatus for applying insulation or other covering to wires and the like, comprising means for moving the wire vertically downwardly, means for reversing the direction of movement of the wire, means for applying a covering to the portion of the wire which moves downwardly, means for applying an impregnating material to the covered wire during its reversal of movement, and ironing and smoothing means for acting upon the portion of the covered and impregnated wire which moves vertically upwardly.

3. Apparatus for applying insulation or other covering to wires and the like, comprising means for applying a covering to the wire, means for applying an impregnating material to the covered wire, means for thereafter moving the wire in a vertical path, means for ironing and smoothing the covered and impregnated wire during its vertical movement, and means arranged above the last-mentioned means for drying the wire.

4. Apparatus for applying insulation or other covering to wires and the like, comprising means for effecting longitudinal movement of the wire in one direction, a pulley for reversing the direction of movement of the wire, means disposed in advance of said pulley for applying a covering to the wire, a pan adapted to contain an impregnating material through which the covered wire is passed by said pulley, and ironing and smoothing means and a heating device arranged to act upon the covered and impregnated wire after it leaves said pulley.

5. Apparatus for applying insulation or other covering to wires and the like, comprising means for effecting longitudinal movement of the wire in one direction,

means for reversing the direction of movement of the wire, means arranged in advance of the reversing means to apply a covering to the wire and ironing and smoothing means arranged to act upon the covered wire after it leaves said reversing means.

6. Apparatus for applying insulation or other covering to wires and the like, comprising means for effecting longitudinal movement of the wire in one direction, means for reversing the direction of movement of the wire, means arranged in advance of the reversing means to apply a covering to the wire, means for applying an impregnating material to the covered wire, and ironing and smoothing means and a heating device arranged to act upon the covered and impregnated wire after reversal of its direction of movement.

7. Apparatus for applying insulation or other covering to wires and the like, comprising means for effecting longitudinal movement of the wire in one direction, a pulley for reversing the direction of movement of the wire, means disposed in advance of the pulley for applying a covering to the wire, a pan adapted to contain an impregnating material through which the covered wire is passed by said pulley, ironing and smoothing means arranged to act upon the covered and impregnated wire after it leaves said pulley, and means to return the excess impregnating material removed from the wire by said ironing and smoothing means to said pan.

8. Apparatus for applying insulation or other covering to wires and the like, comprising means for applying a covering to the wire, feeding means including a friction clutch for effecting longitudinal movement of the wire and means to control the acceleration and retardation of said feeding means.

9. Apparatus for applying insulation or other covering to wires and the like, comprising means for applying a covering to the wire, feeding means including a friction clutch for effecting longitudinal movement of the wire and means including a fly wheel to control the acceleration and retardation of said feeding means.

10. Apparatus for applying insulation or other covering to wires and the like comprising means for applying a covering to the wire, feeding means including a friction clutch for effecting longitudinal movement of the wire and means to control the acceleration and retardation of said feeding means and said covering applying means.

11. Apparatus for applying insulation or other covering to wires and the like, comprising actuating means, means operated from said actuating means to effect longitudinal movement of the wire, a fly wheel operated from said last-named means, a

friction clutch interposed between said actuating means and the means for effecting longitudinal movement of the wire, and means for applying a covering to the wire.

12. Apparatus for applying insulation or other covering to wires and the like, comprising actuating means, means operated from said actuating means to effect longitudinal movement of the wire, a fly wheel operated from said last-named means, a friction clutch interposed between said actuating means and the means for effecting longitudinal movement of the wire, a friction brake operating to frictionally arrest motion of the fly wheel and the means for effecting longitudinal movement of the wire upon disengagement of said friction clutch, and means for applying a covering to the wire.

13. Apparatus for applying insulation or other covering to wires and the like, comprising means for effecting longitudinal movement of the wire, means for applying a covering to the wire, a heating device adapted to be moved to and from an operative position with respect to the wire, and means whereby such movements of the heating device control the actuation of said means for effecting longitudinal movement of the wire.

14. Apparatus for applying insulation or other covering to wires and the like, comprising means for effecting longitudinal movement of the wire, means for applying a covering to the wire, actuating means for said last-named means, a friction clutch interposed between the means for effecting longitudinal movement of the wire and the actuating means, a heating device movable to operative and inoperative positions with respect to the wire, and means whereby such movements of the heating device control said friction clutch.

15. Apparatus for applying insulation or other covering to wires and the like, comprising feeding means for effecting longitudinal movement of the wire, means for applying a covering to the wire, a heating device movable to operative and inoperative positions with respect to the wire, and means whereby the movement of the heating device to its operative position sets said feeding means in operation and movement of the heating device to its inoperative position throws said feeding means out of operation.

16. Apparatus for applying insulation or other covering to wires and the like comprising means for effecting longitudinal movement of the wire, means for applying a covering to the wire, a rotary member through which the covered wire passes, a die carried by said member and over which the covered wire passes, a shaft rotatably mounted on said member, a plurality of ironing and smoothing devices carried by said shaft and

coöperating with said die, tension means forcing said ironing and smoothing devices against the wire after it passes over the die, and means for independently adjusting each 5 of said tension means.

17. Apparatus for applying insulation or other covering to wires and the like, comprising means for effecting longitudinal movement of the wire, means for applying a 10 covering to the wire, a rotary member through which the covered wire passes, a die carried by said member and over which the covered wire passes, a shaft rotatably mounted on said member, an ironing and 15 smoothing device carried by said shaft and coöperating with said die, means for effecting the rotary movement of the die and ironing and smoothing device about the axis of the covered wire, and means for rotating 20 said shaft to move the ironing and smoothing device from its operative position with respect to the die to an inoperative position.

18. Apparatus for applying insulation or other covering to wires and the like, comprising means for effecting longitudinal movement of the wire, means for applying a covering to the wire, and ironing and smoothing mechanism arranged to act upon the covered wire comprising a die adjacent 30 which the covered wire passes, means to adjust said die toward and away from the axis of the wire, and an ironing and smoothing device arranged to coöperate with the die in smoothing and compacting the covering on 35 the wire.

19. Apparatus for applying insulation or other covering to wires and the like, comprising means for effecting longitudinal movement of the wire, means for applying a 40 covering to the wire, and ironing and smoothing mechanism arranged to act upon the covered wire comprising a die adjacent which the covered wire passes and having a channel-like recess to accommodate the 45 wire, a plurality of ironing and smoothing devices yieldingly held toward the die and arranged to coöperate therewith in smoothing and compacting the covering on the

wire, and means for effecting rotary movement of the die and the ironing and smoothing devices about the axis of the wire. 50

20. A wire covering machine comprising means for effecting longitudinal movement of the wire, means for applying a covering thereto, and a drying device comprising a 55 heated shell through which the covered wire passes, and means to move said shell to and from operative relation with respect to the wire.

21. A wire covering machine comprising 60 means for effecting longitudinal movement of the wire, means for applying a covering thereto, and a drying device comprising a shell having a central opening through 65 which the wire passes when the heating device is in its operative position, means to move the heating device to an inoperative position, said heating device having a lateral opening to permit the same to be moved to operative and inoperative positions, and 70 means to heat said shell.

22. A wire covering machine comprising means for effecting longitudinal movement of the wire, means for applying a covering thereto, and a drying device comprising a 75 shell and means whereby said drying device may be moved to and from an operative position in which the wire passes axially through the shell, and a plurality of burner tubes disposed outside of said shell. 80

23. A wire covering machine comprising means for effecting longitudinal movement of the wire, means for applying a covering thereto, a drying device including a shell, 85 which device is capable of movements to and from an operative position in which the wire passes axially through the shell, a plurality of burner tubes disposed outside of said shell, a swinging bracket on which said shell and the burner tubes are mounted, said 90 bracket having a central passage communicating with the burner tubes, and means to supply the central passage of said bracket with fuel.

In testimony whereof I affix my signature. 95
JOHN ALLEN HEANY.
